(57) **CLAIM**

The ornamental design for a packaging assembly, as shown and described.

DESCRIPTION

FIG. 1 is a front perspective view of a packaging assembly according to a first embodiment of our design shown in a first configuration thereof;

FIG. 2 is a front elevation view of the packaging assembly of FIG. 1;

FIG. 3 is a back elevation view of the packaging assembly of FIG. 1;

FIG. 4 is a right elevation view of the packaging assembly of FIG. 1;

FIG. 5 is a left elevation view of the packaging assembly of FIG. 1;

FIG. 6 is a top elevation view of the packaging assembly of FIG. 1;

FIG. 7 is a bottom elevation view of the packaging assembly of FIG. 1;

FIG. 8 is a front perspective view of the packaging assembly of FIG. 1 in a second configuration;

FIG. 9 is a front elevation view of the packaging assembly of FIG. 9;

FIG. 10 is a back elevation view of the packaging assembly of FIG. 9;

FIG. 11 is a right side elevation view of the packaging assembly of FIG. 9;

FIG. 12 is a left side elevation view of the packaging assembly of FIG. 9;

FIG. 13 is a top elevation view of the packaging assembly of FIG. 9; and,

FIG. 14 is a bottom elevation view of the packaging assembly of FIG. 9.

Diagonal shading is used to represent features that are translucent.

Alternating long and short dashed broken lines are used to represent environmental features that are at least partially visible through any translucent surfaces and themselves form no part of the claimed design.

Short dashed broken lines illustrate features and text that are environmental only and form no part of the claimed design.
